UNITED STATES PATENT OFFICE.

FRANK NELSON OLCOTT, OF NEW YORK, N. Y., ASSIGNOR TO BLACK & BOYD MANUFACTURING COMPANY, OF NEW YORK, N. Y., A CORPORATION OF NEW YORK.

DESIGN FOR AN ELECTRIC BRACKET.

44,181.

Specification for Design.

Patented June 10, 1913.

Application filed April 10, 1912. Serial No. 689,912. Term of patent 3½ years.

To all whom it may concern:

Be it known that I, FRANK NELSON OLCOTT, a citizen of the United States, and resident of the borough of Manhattan, city, county, and State of New York, have invented a new, original, and ornamental Design for an Electric Bracket, (Case E,) of which the following is a specification, reference being had to the accompanying drawing, forming a part thereof.

The drawing represents a front elevation of an electric bracket, showing my new design.

The essential features of the design com-

prise the paneled body with ornamental ends; the outside panels being ornamental, fluted, columns and the center panel being a sunken figure with an ornamental upper end; and curved, ornamental, arms springing out of the base below the column, carrying enlarged, ornamental, bases for lamps.

I claim:

The ornamental design for an electric bracket, as shown and described.

FRANK NELSON OLCOTT.
